UNITED STATES PATENT OFFICE.

CORNELIUS B. CORCORAN, DECEASED, LATE OF NEW YORK, N. Y., BY MICHAEL J. CORCORAN, ADMINISTRATOR, OF BROOKLYN, NEW YORK, AND ALFRED G. F. KUROWSKI, OF BROOKLYN, NEW YORK, ASSIGNEES TO UNDERWOOD ELLIOTT FISHER COMPANY, OF NEW YORK, N. Y., A CORPORATION OF DELAWARE.

TYPEWRITING MACHINE.

Original application filed December 30, 1922, Serial No. 609,793. Divided and this application filed February 11, 1926. Serial No. 87,530.

This invention relates to sound-deadening casing for typewriting machines. More particularly, to certain features thereof, the invention relates to a combined carrying and sound-deadening casing, that is to say, to a casing in which a portable machine may be carried by hand from place to place and in which the machine may be operated.

In a casing of this kind, the side, rear and bottom walls of the carrying case may without transformation serve as the side, rear and bottom walls of an interior sound-deadening casing. A cover is provided for the interior sound-deadening casing which may be swung upwardly to permit access to the machine.

To enable the operator to insert readily or remove the machine from the casing, the front wall of the interior casing is made of two pieces, to wit, a lower and an upper plate. The lower plate is attached to the carrying case and its central portion is cut away to allow the keyboard of the typewriting machine to protrude therethrough. The upper plate which may be attached to, or detached from, the lower plate is so constructed that when held in position on the lower plate it will close the opening above the keyboard, and assist in holding the machine in place.

A feature of the present invention is the provision of means for attaching the upper plate to the lower plate, said means consisting of latches, one on each side of the plate, each latch having its hook portion pivotally mounted on the lower plate, and a pin on the upper plate which is engaged by the hook portion when the upper plate is moved into position on the lower plate, thereby holding the former in position. For limiting the throw of the hook to operative or inoperative positions, the lower part of the hook is provided with a yoke which engages a pin on the lower plate, thereby limiting the throw of the hook in either direction.

Another feature of the invention relates to novel means near the rear of the cover and upon which the latter is swingably mounted. Said means are in the form of hinges, of which one at each side, between the cover and the side wall of the casing, is provided.

Still another feature of the invention relates to novel means for holding the cover in its closed position. Said means may com-

prise a stirrup on the cover and a hook pivoted on the front wall of the casing, the hook being attached to engage the stirrup when the cover is closed and hold the same in its closed position, means being provided for releasing said hook from the stirrup. Since it is desired to place the hook and the stirrup in the inside of the casing, means is provided at the exterior of the casing which is operatively connected to the hook, thereby enabling the operator to release the hook from the exterior of the casing.

Still another feature of the invention relates to novel means for closing the slot in the top of the cover through which various levers and arms on the carriage project. Said means comprises cushions, one on each side of the opening, and springs on the under side of said cushions for urging them together.

This application is a division of application, Serial No. 609,793, filed December 30, 1922 (now Patent No. 1,578,399, dated March 30, 1926).

Other features and advantages will hereinafter appear.

In the accompanying drawings,

Figure 1 is a top plan view of the casing; the left-hand side being shown with the cover removed, and the position of the machine being indicated in dotted lines.

Figure 2 is a view, in cross-sectional side elevation, taken on the line 2—2 of Figure 1.

Figure 3 is a front view of the casing and the machine therein; the outside casing-cover having been removed from the casing-body and the latter being seated in the removed cover.

Figure 4 is a view, in cross-section, on the line 4—4 of Figure 3; the interior sound-proof cover being, however, shown as swung up to position for access to the machine.

Figure 5 is a front view of the casing with the outer cover locked thereon for transportation; the casing being broken away at the right-hand end to show certain details within the same.

Figure 6 is a view, looking at the interior of the cover, of the cushions which form the slot for the operating levers on the carriage, and of the means whereby the same are secured to the casing-cover.

Figure 7 is a detail view, in cross-sectional side elevation, showing the means whereby the rear of the window-pane is held to the cover, and showing the cushion which forms the front wall of the slot for the levers on the carriage and the attachments of the same to the cover.

Figure 8 is a rear view of the device for locking down the interior sound-proof cover. The casing comprises a body-portion 15 and an outside cover-portion 16. The parts 15 and 16 have hinge-plates 17 and 18, respectively, secured thereto; and the plates 17 have fixed thereto hinge-pins 19 for receiving the plates 18. In the lower edges of the front wall of the cover-part 16 (see Figure 2) are pins 20, adapted, when the cover is in closed position on the body-portion 15, to be received in pockets or recesses 21 in the forward edge of the part 15. A lock 22, of any suitable character, operable by a key adapted to be set into the key-hole 23 in the front wall of the cover 16, serves to secure the cover 16 to the body-part 15. The assembled casing with the machine therein may be carried by means of a handle 24 on the cover 16. When so carried by the handle 24, the pins 20 serve to support the body-part 15, and machine, from the cover. When the lock 22 is released and the cover 16 swung around the hinges 19 sufficiently to clear the pins 20 of the recesses 21, the cover-part may be shifted longitudinally leftward to clear the hinge-plates 18 thereon from the hinge-pins 19; whereupon the cover-part 16 may be lifted from the body-part 15, and, if desired, placed in the position shown in Figure 4, wherein the body-part 15, with the machine thereon, is shown as seated in the inverted cover. Preferably the cover has side flanges 25 (see Figure 3), which are adapted to fit over the side walls 26 of the body-part in both the Figure 2 and Figure 4 positions.

The body-portion 15 of the casing is divided longitudinally by a plate 27, which extends from one to the other of the side walls 26 thereof. The plate 27 is offset at its lower edge to form a flange 28, through which are passed wood screws 29, securing the plate to the base 30 of the body-part of the casing. The plate 27 may be further braced by means of a strip 31 extending longitudinally thereof on the base 30. A similar strip 32 may be extended from side to side of the body-part, at the forward edge thereof, where the cover engages the base. The plate 27, together with the rear wall 33 of the part 15, and the side walls of the latter, forms an interior chamber adapted to receive the main frame 34 and the carriage 35 of the machine. The keyboard-extension 36 of the machine protrudes through, and forward of, the plate 27, so that the keyboard may be accessible when the outer cover 16 is removed. This interior chamber has the rear wall thereof lined with

sound-deadening material 37; the side walls thereof with sound-deadening material 38; the base thereof with sound-deadening material 39; and the front thereof with sound-deadening material 40, which latter is suitably secured to the plate 27. This interior chamber is also provided with a cover 41, hinged at 42 to the casing side walls 26, and adapted to be swung from its normal, Figure 2, position, to the position shown in Figure 4, in which latter position access may be had to the machine, for erasures and the like.

For centering and holding the machine to the casing base 30, the rear feet 43 of the machine are moved into brackets 44 and the front feet 45 into disks 46. The front of the machine is then locked against upward movement by a plate 47, secured to the upper edge of the plate 27, and which crosses over, and fits down upon, the front plate 48 of the machine, as shown in Figure 3. This plate 47 is provided with a sound-deadening lining 49 and forms an upward continuation of the front wall of the interior chamber to the lower front edge of the interior cover 41 when the latter is in normal, Figure 2, position.

In order that the plate 47 may be readily removed for the insertion of the machine, and thereafter locked in place upon the plate 27, the following means are provided. In the upper edge of the plate 27, one at each side thereof, are two vertical slots 50. Fast to the plate 47, and adapted to register with the slots 50, are pins 51 which project inward from the plate 47 through the lining of the latter, and through slots in the lining 49 of the plate 27, to a point beyond the inferior face of the latter lining. When the pins 51 are registered with the slots 50, the plate 47 may therefore be lowered into Figure 3 position for engagement with a shoulder 52 on the plate 27, and for engagement with the front wall 48 of the machine. In this position, hooks 53, pivoted at 54 to the plate 27, are adapted to have their noses 55 snapped over the pins 51, to lock the plate 47 down against upward displacement. As shown in Figure 2, the hooks 53 are spaced from the plate 27, by means of collars 56 on the pivot-pins 54. Each hook 53 has a finger 57 integral therewith. As shown in Figure 2, the lower part of the hook 53 is offset forward at 58, and then upward in the form of a yoke 59. The yoke 59 loosely embraces a stop-pin 60, fast to the plate 27; and the throw of the hook, in either direction, is determined by the engagement of one or the other of the arms of the yoke with the pin 60. The pin 60 also serves as anchorage for one end of a spring 61, the other end of which is secured by a pin 62 to the hook. The tension of the spring is such as to urge the hook in a direction to lock, and hold locked, the plate 47, upon the plate 27. The lining 49 on the plate 27 is suitably cut away or recessed, to receive the yoke 59 of

the hook, and to allow for movement of the latter with the hook.

The cover is pivotally connected to the casing side walls 26 in the following manner.

- 5 Secured, by means of wood screws 63, to the walls 26 are disks or plates 64, having bushings 65 integral therewith and offset into countersinks in the walls 26. These bushings serve as journals for pivot-pins 66. The pins 66 are held to the cover-wall 41 by U-shaped members or yokes 67, each of which has a flange 68 to receive screws 69, for holding the U-pieces to the cover. The pivot-pins 66 are held against longitudinal movement in the U-pieces, and in the bushings 65, by set-screws 70 in the U-pieces. The pivot-pins (see Figure 5) project at 71 beyond the ends of the U-pieces; and such projecting ends have grooves 72, to receive the finger-nail, or other implement, for sliding the pins in and out of the bushings 65 when the set-screws 70 are loosened; thus permitting the cover 41 to be mounted in the casing, or to be removed, expeditiously, and at will. The cover, like the rest of the interior casing, is provided with a lining 73; and this lining is provided with a facing-piece 74, of sheet-metal or other material, to prevent fouling of the paper, in the machine, on the lining 73 as the carriage is moved in letter-feed and return directions. As indicated in Figure 2, the lining 73 is recessed to receive the U-pieces 67 and pivot-pins; and, to permit of access to the pivot-pins and to the set-screws, the facing-piece 74, as shown in Figure 5, is cut away at 75.

As hereinbefore stated, the normal position of the cover 41 is that shown in Figure 2. The lower edges of the side lining-members 76 of the cover are held by strips 77; and screws 78 pass through the cover and through the lining 76 and thread into the strips 77. Also held by the strips 77 and screws 78 (see Figure 5) are side cushions 79, by means of which the cover, at the sides thereof, is supported on the upper edges of the side lining-members 38 of the casing-part 15. These cushions consist of lengths of rubber tubing 80, wrapped in strips 81, of flexible material, such as felt, the edges of which strips are brought together at 82 between the side walls 83 of the cover and the retaining strips 77, heretofore mentioned. The screws 78 pass through the gathered ends of the felt 81.

In the front of the cover is a window, through which the writing on the platen may be observed. A window-pane 84, of glass or other transparent material, is set into a frame provided therefor in the cover. In the drawings, the pane is shown as comprising superposed sheets of glass 85, 86 (see Figure 7). At the sides of the window are metal plates 87, secured to the cover by screws 88, which plates, at the edges thereof, underlie the edges of the lower pane 86, and serve as shelves on which the window-panes are supported from

the cover. At the front of the window, the forward edge of the pane 85 is supported by a flange 89 on a metal strip 90, secured by screws 91 to the lower front edge of the cover. The strip 90 and screws 91 serve also to hold to 70 the cover a cushion 92 similar in all respects to the side cover-supporting cushions 79, and which rests upon an offset 93 on the upper edge of the removable front plate 47, when the cover is in normal position. At the rear 75 of the window, a metal strip 94 serves as a supporting shelf for the rear edge of the pane 85, and this strip 94 is held to the cover-plate 41 by screws 95.

The cover is normally locked down in Figure 80 2 position. When, however, the cover is unlocked, it is adapted to be automatically thrown open, that is, to Figure 4 position, by a spring-device (not shown).

The cover is held against opening by a lock 85 (see Figures 3 and 8) at the front wall of the interior casing. This lock consists of a hook 96, pivoted at 97 to the plate 27, and held suitably spaced therefrom by a collar 98 on the pivot-pin 97. The nose 99 of the hook is 90 adapted to be engaged in a stirrup 100, depending from the cover-plate 41, at the left-hand side of the window, and having a flange 101 at its upper end to receive a screw 102, by means of which the stirrup is held to the cover. 95 The nose 99 of the hook is carried by a piece 103, adjustable up and down, with respect to the hook-proper 96, for accurate determination of the correct locked position of the cover and casing-proper. To permit of such 100 adjustment, headed screws 104 on the hook-proper pass through slots 105 in the adjustable part 103. The locked position of the hook is determined by a stop-pin 106 on the plate 27. This pin also serves as anchorage 105 for one end of a spring 107 (see Figure 8), the other end of which spring is connected to a pin 108 on a finger 109 of the hook-proper. The spring 107 acts automatically to throw the hook to cover-locking position, and to hold 110 the same in such position. For moving the hook to unlock the cover, there is pivotally connected thereto, at 110, a link 111, the other end of which link is pivotally connected at 112 to an arm 113, fast on a rock-shaft 114, 115 journaled in the front plate 27. The shaft 114 passes through the front plate, and, on the outside of the front plate, has fast thereto an arm 115, carrying a finger-piece 116. Depression of the finger-piece 116 causes the arm 120 115 to be rocked in such manner as to draw on the link 111, and release the hook; whereupon the spring-device, heretofore mentioned, throws open the cover.

Since the machine is to be operated in the 125 sound-proof inner casing, and since the side walls 26 of the casing-part 15 form also the side walls of the interior sound-proof chamber, the length of the several parts of the casing must be such as to allow for full move- 130

ment of the carriage in letter-feed and return directions on the machine. Secured to the carriage, however, are various operating levers and arms which should be accessible from the outside of the sound-proof chamber. These levers and arms comprise a line-space lever 117, for operating line-space mechanism 117^a, a carriage-rack-release lever 118, for disengaging a rack 118^a from the escapement 5 pinion 118^b, and a carriage-return arm 119. If they are to project to the outside of the sound-proof chamber, the latter must be slotted to permit them to travel therealong with the carriage. Such a slot is shown at 120 15 in the cover at the rear of the window-pane. If this slot is open, however, undesirable noise will be emitted therethrough. Consequently, resilient cushions 121 are provided which come together to close the slot, except 20 at the points where the levers and arms protrude therethrough. These cushions (see Figures 2 and 7) are a forward cushion 122 and a rearward cushion 123. The cushions are identical in construction, consisting of an 25 inner flattened tube 124, of flexible material, embraced and supported by a strip 125, of flexible material, such as felt, the ends of which are brought together and secured to the cover-plate. As to the forward cushion, the 30 felt edges are brought between the rear window-pane-supporting strip 94 and cover-plate 41. The screws 95, which hold the strip 94, pass through and hold the edges of the felt 125. The edges of the felt 125 of the rear 35 cushion are similarly brought together between the cover-plate 41 and a metal strip 126, which is held to the cover-plate by screws 127, which pass through the gathered edges of the felt and thread into the strip 126. Each 40 cushion also comprises a coil-spring 128, which extends longitudinally the full length thereof, and the ends of which are set on pins 129 in bracket-plates 130. Each plate 130, at the forward end thereof, is provided with an 45 ear 131, by means of which it is secured to the window-retaining strip 94, and, at its rear end, with an ear 132, by means of which it is secured to the retaining strip 126. The coils 128, as shown in Figure 2, are set against the 50 flexible cushion-parts 124 in such position as to yieldingly hold the latter together, to close the slot between the same. In addition to their end supports on the plates 130, the coils 55 are held to the cushion-parts 124 at intervals throughout their length by spring-clips 133 (see Figure 7). These clips are curved to embrace the coils, and have flattened tongues 134, adapted to be inserted between the retaining strips 94 and 126, as the case may be, 60 and the gathered ends of the cushion-holding felt between such strips and the cover-wall 41. In forcing the clips into position, the felt is compressed, and, being thereafter under compression, exerts a frictional hold on 65 the clips which prevents their accidental dis-

placement. The clips may, therefore, be positioned and removed without manipulation of any special attaching means therefor; and, being held, as above stated, may be positioned wherever desired along the cushions, 70 and in any desired number. Preferably the clips for holding the coil of the rear cushion are staggered with respect to the clips for holding the coil of the front cushion. This is so, in order that two opposed and immediately-registering clips, one bearing on each cushion, may not offer too great a resistance to movement of the levers with the carriage along the cushions. As has been stated, the clips themselves are flexible, and, if made 75 sufficiently flexible, might even be directly opposed to each other on the two cushions.

Variations may be resorted to within the scope of the invention, and portions of the improvements may be used without others. 80

Having thus described the invention, we claim:

1. A sound-deadening casing for a type-writing machine having a slot or joint therein and a cushion for closing the slot or joint, 90 including a strip of flexible fabric attached to the casing at one side of the joint and adapted to have its face bear upon the other side of the joint, a coil spring set against the rear of the strip of fabric longitudinally 95 thereof, and spring clips for holding the coil spring to the fabric strip.

2. A sound-deadening casing for a type-writing machine having a slot or joint therein and a cushion for closing the slot or joint, 100 including a strip of flexible fabric attached to the casing at one side of the joint and adapted to have its face bear upon the other side of the joint, a coil spring set against the rear of the strip of fabric longitudinally 105 thereof, and pins on the casing at the ends of the slot for receiving and supporting the open ends of the coil spring.

3. A sound-deadening casing for a type-writing machine having a slot or joint therein and a cushion for closing the slot or joint, 110 including a strip of flexible fabric attached to the casing at one side of the joint and adapted to have its face bear upon the other side of the joint, a coil spring set against the rear of the strip of fabric longitudinally 115 thereof, and means for supporting the coil spring intermediate its ends.

4. A sound-deadening casing for a type-writing machine having a slot longitudinal 120 thereof through which may project and along which may travel an operating arm or lever on the carriage of the machine, and cushions extending longitudinally of the slot, one on each edge thereof and adapted to bear against each other to close the slot, the cushions comprising strips of flexible fabric attached to the casing on the opposite sides of the slot, and spring clips in engagement with the rear 125 faces of the cushions at intervals therealong 130

to urge the same together, said clips being staggered with respect to each other.

5. A sound-deadening casing for a type-writing machine having a slot longitudinal thereof through which may project and along which may travel an operating arm or lever on the carriage of the machine, and cushions extending longitudinally of the slot, one on each edge thereof and adapted to bear against each other to close the slot, the cushions comprising strips of flexible fabric attached to the casing on the opposite sides of the slot, and coil springs in engagement with the rear faces of the cushions to urge the same together. 10

15

6. A sound-deadening casing for a type-writing machine having a slot longitudinal thereof through which may project and along

which may travel an operating arm or lever on the carriage of the machine, and cushions extending longitudinally of the slot, one on each edge thereof and adapted to bear against each other to close the slot, the cushions comprising strips of flexible fabric attached to the casing on the opposite sides of the slot, coil springs in engagement with the rear faces of the cushions to urge the same together, and spring clips at intervals along the cushions in contact with the coil springs to hold the coil springs to the flexible strips, 20 25 30

said cushions contacting interiorly of the casing within the outer surface thereof.

MICHAEL J. CORCORAN,
Administrator of the Estate of Cornelius B. Corcoran, Deceased.

ALFRED G. F. KUROWSKI.
